James Boyd
INVENTOR, BY
Charles H. Woodward, Atty.

UNITED STATES PATENT OFFICE.

JAMES BOYD, OF ST. PAUL, MINNESOTA.

HOISTING APPARATUS.

SPECIFICATION forming part of Letters Patent No. 441,742, dated December 2, 1890.

Application filed April 28, 1890. Serial No. 349,772. (No model.)

To all whom it may concern:

Be it known that I, JAMES BOYD, a citizen of the United States, residing at St. Paul, in the county of Ramsey and State of Minnesota, ⁵ have invented certain new and useful Improvements in Hoisting Apparatus, of which the following is a specification.

This invention relates to that class of hoisting apparatus employed in elevating the material in the erection of buildings; and it consists in the construction, combination, and arrangement of parts, as hereinafter shown and described, and specifically pointed out in the claims.

¹⁵ In the drawings, Figure 1 is a side elevation, partially in section, of the upper part of the frame of the apparatus, with my improvements attached thereto. Fig. 2 is an end elevation, and Fig. 3 is a plan view of the same. ²⁰ Fig. 4 represents the guide-cable tightening device detached. Fig. 5 is a cross-sectional view through the center of the frame, illustrating the construction of the combined brake and cage-releasing lever. Fig. 6 is a front view, Fig. 7 is a plan view, and Fig. 8 is a ²⁵ sectional side view, enlarged, of the clip for holding the guide-cables. Fig. 9 is a perspective view of the same.

The horse or frame portion consists of two ³⁰ channel-iron sides A' A², connected at their ends by castings B', in which also the legs B² of gas-pipe are supported, as shown.

³⁵ Journaled across the sides A' A² are two grooved cable wheels or sheaves E', over which the cables for hoisting the "cages" run. These cages carry the material to be elevated, and are shown in Patents No. 271,681 and No. 308,340, granted to me February 6, 1883, and November 25, 1884; but, as they are ⁴⁰ not necessarily a part of the present invention, they are not shown.

Each of the sheaves E' is provided with a ⁴⁵ brake-strap E², each strap being fastened by one end at a' to the end castings B', and with the other ends pivoted at a² to crank-levers D, the latter being in turn pivoted at their "elbows" b between the sides A' A² of the frame. One arm of each of these crank-levers D projects downward, and is provided ⁵⁰ with a barbed or inclined catch d', while the other end of each is pivoted at d² to levers F, the latter being in turn pivoted at e between

the sides A' A², and with their free ends g' lying alongside each other and within a slot g² in a lever G', as shown. This lever G' is pivoted at g³ by a bracket H' upon the lower side of the side piece A', and with an arm G², projecting from one end, and with a socket G³ on the other end, in which the handle G⁴ is secured. The pivot g³ passes through a slot 55 in the lever G', so that the lever may be held back with the point g⁵ of the arm G² in contact with the under side of the side piece A², as in Fig. 2, or pushed backward until the point g⁵ is clear of the side piece A², as in Fig. 65 5. By this means the lever G' is utilized to perform two functions—viz., to throw the hooked ends d' of the crank-arms D to one side to disengage them from the corresponding hooks d³ on the castings K', by which the cables K² are connected to the cages, and thus release the cages when they are required to descend, and, second, to throw the brake-straps into action, and thus serve as a brake-lever. When the point g⁵ of the lever G' is in position against the lower side of the side piece 75 A², the handle G⁴ can be actuated only by being moved upward, which action will disengage the hooks d' from the hooks d³, but will not affect the brake-straps; but if the brakes are to 80 be set the lever G' will be pushed backward until the point g⁵ is clear of the side A², as in Fig. 5, when the lever G' is free to be drawn downward, which action will cause the brake-straps to be drawn downward upon the sheaves 85 E', and thus "brake" the cages and regulate their motion.

The side pieces A' A² are each provided with a truss-rod A³, arranged with their ends held in the end castings B' and with their centers supported by a hook H² on the bracket H' or by any other suitable means to assist in carrying the strains and to prevent the sagging of the "horse" or frame.

N' N² N³ N⁴ represent the guide-cables between which the cages run up and down, and are held by their lower ends in clips M. (See Fig. 1.) One face of this clip is formed with a half-round groove m', this groove being smaller at its center m² than at the ends, and with "U-bolts" m³—one on each side of the central shallow part m² of the groove m'—so that when the cable is clamped fast to the clip by the U-bolts the shallow portion will cause it ⁹⁵ ¹⁰⁰

to assume an angular or curved form, as shown at m^4 in Fig. 8, and thus increase the holding-power of the clip.

Jounaled upon top of the side A' at points 5 corresponding to the guide-cables N' N² N³ N⁴ are small drums formed with disks n', shanks n², ratchets n³, and square or other irregular shaped nuts n⁴, the nuts and disks having slots or grooves n⁶ formed through them for 10 the reception of the cables. The shanks n² are secured to the side A' by cap n⁵, and the same cap also has a pawl n⁷, adapted to engage with the ratchet n³. By these simple devices 15 the guide-cables may be tightened to as great an extent as desired by simply inserting them through the slots n⁶ and turning the drum by a wrench placed upon the nuts n⁴; the pawl acting upon the ratchets and holding the tension when obtained, the unused portion of 20 the cables lying across the face of the horse or frame and being coiled up out of the way.

The guide-cables N' N² N³ N⁴ are necessarily as long as the highest building in which the machine is to be employed, the surplus 25 of the cables being coiled upon or near the horse, and as the horse is moved from story to story as the building progresses the cables must be released and grasped at a higher point; hence it will be readily seen that a very im- 30 portant advantage of this form of tightening and holding drum is the facility with which the guide-cables can be grasped and held at any point.

It is only necessary, as before stated, to insert the cables into the slots n⁶ of the drum, 35 wind it one-half a turn around the drum, and then revolve the drum by the wrench to tighten and firmly hold the cable.

Having thus described my invention, what 40 I claim as new is—

1. In a hoisting apparatus of the class de- 45 scribed, a horse or frame adapted to support the cable-sheaves E', brake-straps E², bearing upon said sheaves, crank-levers pivoted to said horse or frame and having hooks on their

lower ends adapted to engage with corresponding hooks on the cages containing the material to be elevated, and connected to said brake-straps, and means whereby the movement of said crank-levers will release said cages and set said brakes, substantially as and for the purpose set forth. 50

2. In a hoisting apparatus of the class de- 55 scribed, a horse or frame adapted to support the cable-sheaves E', brake-straps E², bearing against said sheaves, crank-levers D, pivoted to said horse or frame and having hooks on their lower ends adapted to engage with corresponding hooks on the cages containing the material to be elevated, and connected to said 60 brake-straps, levers F, pivoted to said horse or frame and also to said crank-arms, and a lever G', pivoted to said horse or frame and also to said levers F, and provided with arm G², whereby when said lever G' is moved in 65 one direction said cages will be released and when moved in the opposite direction said brakes will be set, substantially as and for the purpose set forth.

3. In a hoisting-machine of the class de- 70 scribed, a horse or frame carrying the hoisting-cables by which the cages are raised and lowered, and guide-cables for said cages, in combination with devices for tightening and holding the said cables, consisting of the drums 75 having the disks n', provided with slots n⁶, through which the cables are adapted to be passed and wound around said drums, and with ratchet n³, and adapted to be held in place by pawl n⁷, whereby said cables may 80 be held at any point in their lengths, substantially as and for the purpose set forth.

In testimony whereof I have hereunto set my hand in the presence of two subscribing witnesses.

JAMES BOYD.
